UNITED STATES PATENT OFFICE.

ANTON LOUKOTA, OF SCHENECTADY, NEW YORK.

FOLDING UMBRELLA.

No. 922,925.

Specification of Letters Patent.

Patented May 25, 1909.

Application filed April 22, 1908. Serial No. 428,578.

To all whom it may concern:

Be it known that I, ANTON LOUKOTA, a citizen of the United States, residing at Schenectady, in the county of Schenectady and State of New York, have invented new and useful Improvements in Folding Umbrellas, of which the following is a specification.

This invention relates to umbrellas, and it has for its object to provide an umbrella of simple and improved construction which may be readily collapsed or folded in small compass, so that it may be conveniently carried in a trunk, traveling bag or suit-case, or even in a pocket, if so desired.

The objects of the invention are to simplify and improve the construction and operation of this class of umbrellas; and with these and other ends in view which will readily appear as the nature of the invention is better understood, the same consists in the improved construction and novel arrangement and combination of parts, which will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the invention may be resorted to when desired.

In the drawing—Figure 1 is a side elevation of a portion of the frame of an umbrella constructed in accordance with the invention, one of the ribs of the frame being shown raised or extended. Fig. 2 is a side elevation showing the portion of the umbrella frame illustrated in Fig. 1, collapsed or folded. Fig. 3 is a sectional detail view taken longitudinally through a portion of the stick and the runner, on the plane indicated by the line 3—3, in Fig. 1. Fig. 4 is a sectional detail view taken on the line 4—4, in Fig. 1. Fig. 5 is a sectional detail view taken on the line 5—5, in Fig. 1. Fig. 6 is a sectional elevation of one of the clamps connecting the braces with the ribs. Fig. 7 is an inverted plan view showing the joint connecting members or sections of one of the ribs.

Corresponding parts in the several figures are denoted by like characters of reference.

The stick A of the improved umbrella is preferably made of metal tubing, and it is composed of a plurality of sections 1, 2 and

3, telescoping together, the section 1 at the ferrule end being of larger diameter than the remaining sections, which collapse within the said section 1; and the smallest section 3, being equipped with a knob or handle 4. The section 1 carries the ferrule 5 and the crown 6 upon which the ribs 9 are hingedly mounted in the usual manner; said section 1 also carries the longitudinally slidable runner 7, which is connected with each of the ribs by means of a brace 8. Each of the ribs is composed of two hingedly connected sections 9 and 10; the inner section 9 being hingedly connected with the crown 6, and provided at its outer extremity with an inverted U-shaped lap 11, forming lugs or ears 12, 12, which are disposed adjacent to and spaced from the extremity of the section 9, which latter is of U-shaped cross-section, but is terminally compressed to form a lug 13 which is disposed between, but spaced apart from the lugs 12. The outer rib section 10 is equipped with a U-shaped hinge-member 14, having upward extending lugs 15, doubled upon themselves so as to present shoulders 16; said lugs 15 being inserted between the compressed terminals 13 of the rib sections 9, and the adjacent lugs 12 of the laps 11, and there secured by means of transverse pins or pivots 17. The rib sections 10 will thus be hingedly connected with the rib sections 9 in such a manner as to be capable of folding outward upon the latter; when the rib sections 10 are extended, as shown in Fig. 1, the inner extremities of the hinge members 14 will constitute stops that will keep the rib sections 10 in extended position, as shown.

The rib sections 9 are provided intermediate their ends with U-shaped clasps 18 having lugs 19 that are bent or doubled upon themselves to present shoulders 20 abutting upon the lower edges of the rib sections 9; said lugs 19 serving to support the pins 21 upon which the outer ends of the braces 8 are pivoted.

The runner 7 is provided with a thumb lever 22 pivoted upon the band or wire 35 which also serves for the attachment of the braces, and having, between its fulcrum and its outer free extremity, an inward extending downturned nib or projection 23 adapted to engage a notch or slot 24 in the stick section 1 for the purpose of supporting the umbrella frame in extended position; the lower edge of the slot 24 is beveled, as indi-

cated at 25 to engage the correspondingly beveled downturned nib of the thumb lever, which will thus be retained securely against accidental displacement. By pivoting the 5 lever 22 upon the band or wire which also serves for the attachment of the braces, the said lever will be supported in a very safe and rigid manner, and the construction will be found to be thoroughly efficient and durable. The runner sleeve is not weakened by providing it with lugs for the attachment of the lever, and it will be observed that the nib 24 is arranged to engage the lower edge 10 of the runner sleeve, which is simply notched for the accommodation of said nib; thus when the nib enters into engagement with the beveled slot in the stick section 1, it will be forced into said slot by the downward tension to which the runner sleeve is 15 exposed through the medium of the braces when the ribs are extended, and the parts will thus be retained in position without the use of springs which are always cumbersome and liable to get out of order.

25 In practice, the umbrella frame is to be covered with textile fabric, in the usual manner, but such covering has not been illustrated as it does not constitute a part of the invention.

30 From the foregoing description taken in connection with the drawings hereto annexed, the operation and advantages of the invention will be readily understood. The construction is simple and inexpensive; and 35 an umbrella constructed in accordance with the invention may be readily folded or collapsed in very small compass.

Having thus described the invention, what is claimed is:

40 1. In an umbrella, a stick composed of a plurality of sections telescoping together, one of said sections having a ferrule, a runner mounted upon the ferrule carrying section, a crown upon said section, foldable 45 ribs hinged upon the crown and comprising inner and outer rib sections, braces connecting the inner rib sections with the runner,

the latter being provided with a band or wire for the attachment of said braces, and a lever hinged upon said band or wire and 50 having between its fulcrum and its outer extremity a downturned nib adapted to engage a slot in the ferrule carrying section of the stick.

2. In a folding umbrella, a collapsible 55 stick, a crown secured upon one section of the stick, a runner slidably engaging said section, the latter being provided with a notch having a beveled lower edge, foldable ribs hinged upon the crown, braces connecting the ribs with the runner, the latter being provided with a band or wire for the attachment of the braces, and a thumb lever pivoted upon the band or wire of the runner and having between its fulcrum and its outer 60 extremity a downturned nib adapted for engagement with the beveled edged slot in the stick.

3. In a folding umbrella, a rib composed of two cross sectionally U-shaped sections, 70 one of such sections being provided with a terminal lap having eyes or lugs and said section being terminally compressed to form a lug intermediate said eyes, and the second section having a U-shaped hinge member 75 extending around the same and provided with upwardly extending lugs inserted between the compressed extremity of the first section and bent or doubled against themselves to form shoulders or abutments which 80 bear against the edges of the second section and a pivotal pin extending transversely through the lugs of the lap upon the first section and the compressed end of said first section and through the doubled lugs of the 85 hinge member connected with the second section.

In testimony whereof I affix my signature in presence of two witnesses.

ANTON LOUKOTA.
